10 Claims. (Cl. 318—467)

This invention relates to a shaft-positioning mechanism for positioning a rotary shaft in a plurality of predetermined positions and has for its object to provide a shaft-positioning mechanism of this kind which has a higher accuracy and a high speed of positioning. The high accuracy of positioning with the shaft-positioning mechanism according to the invention may be achieved without a large number of very accurately processed parts being required. The said shaft-positioning mechanism is characterized in that it comprises two rotary adjusting members, of which the first adjusting member during the adjustment always determines the end of a sector of the total angle of rotation which this adjusting member can perform, within which sector the ultimately desired position of this shaft is situated and the second adjusting member in the opposite direction of rotation determines the ultimately desired position of the shaft within the sector, determined by the first adjusting member and starting from the end of the sector determined by the first adjusting member, provision being made of a driving shaft which simultaneously drives the two adjusting members with the interposition of the transmission mechanism between the shaft and the first adjusting member having a retardation greater than that of the transmission mechanism between the shaft and the second adjusting member.

In a further embodiment of the invention, all sectors have the same angular value and are whole parts of 360° , the ratio between the speeds of the adjusting members per unit-time being equal to the number of the sectors. Consequently, a uniform division of the positions to be adjusted through 360° may be obtained.

In another embodiment of the invention, the shaft-positioning mechanism is preferably driven electrically, the first adjusting member, hereinafter referred to as the sector-adjusting member, comprising a collector which is so connected to the circuit that, when the chosen sector is reached, the direction of rotation of the driving shaft reverses, a coupling provided between the sector-adjusting member and the collector permitting free movement of the sector-adjusting member with respect to the collector. In this embodiment of the invention, it is thus possible to choose the desired position of the shaft at any arbitrary distance from the shaft proper.

In another embodiment of the invention, if all sectors have the same value, the free movement of the sector-adjusting member with respect to the collector is effected through an angle having the same value or a higher value than the angular value of the sectors.

The second adjusting member which determines the ultimate position of the shaft, is constituted in another embodiment of the invention by two parts, of which one part comprises a ratchet wheel and a collector which is rigidly connected therewith and the other part is an auxiliary member driven by the driving shaft, a coupling provided between said parts allowing of free rotation of the auxiliary member with respect to the ratchet wheel in one direction of rotation, while in the other direction of

2

rotation the auxiliary member can perform a rotation of at most 360° with respect to the ratchet wheel. Consequently, the possible rotation of the sector-adjusting member is determined by the relative positions of the auxiliary member and the ratchet wheel.

In another embodiment of the invention, an electrically operated pawl is provided which can co-operate with the ratchet wheel, the position of the pawl being determined by the position of the collector which is rigidly connected to the ratchet wheel. As soon as the collector has reached a position determined by a selecting collector, the pawl meshes with the ratchet wheel and locks it.

In a further embodiment of the invention, it is possible for the auxiliary member and the ratchet wheel to be arranged on a common shaft so as to be rotatable about this shaft, a friction coupling being provided between the said two parts. However, in another preferred embodiment of the invention, the ratchet wheel together with its collector is driven by a separate shaft, preferably with the interposition of a retarding gear. This embodiment affords advantages, particularly in connection with the desired short time in which the shaft should be adjusted which requires a high speed of the auxiliary member, since in this embodiment of the invention the release time of the relay which controls the pawl is much less important.

In one embodiment of the invention, the shaft to be positioned may be driven by the sector-adjusting member. In this case positions can be adjusted only which are located within an angle of 360° . This suffices in most cases for example, for tuning capacitors, resistors and similar parts. However, if it is desired to adjust also tappings on inductances and similar parts, in which event angles of several times 360° are traversed by the shaft to be positioned, this shaft, in another embodiment of the invention, is coupled directly with the driving shaft.

In order that the invention may be readily carried into effect, it will now be described, by way of example, with reference to the accompanying drawing showing diagrammatically in Fig. 1 the electrical and mechanical structure of a shaft-positioning mechanism.

Fig. 2 is an enlarged diagrammatic showing of the connection between the worm wheel 2 and collector 4. A shaft 1 to be positioned carries a worm wheel 2 which is rigidly connected thereto. The worm wheel 2 carries a pin 3. Rotatably arranged on the shaft 1 is a collector 4 which comprises a conductive ring which contains a small sector 5 having an angular value of less than 10° and which is of non-conductive material. In total are 36 fixed sliding contacts 6 arranged with equal spacings on the periphery of the collector 4. The collector also has a groove 7 in which the pin 3 engages and which occupies an angle of a little more than 10° . This additional value is required in view of the thickness of pin 3. This implies that the worm wheel 2 can cover an angle of 10° in each direction of rotation without the collector 4 being taken along. The worm wheel 2 is driven without backlash by means of a worm 8. Furthermore, a sliding contact 9 is provided which is rigidly arranged and connected to the inner side of collector 4.

The worm 8 is rigidly connected to a driving shaft 10, which carries a screw wheel 11. The screw wheel 11 drives an auxiliary member 12 which also has the form of a screw wheel and which can rotate freely about a shaft 13. The transmission ratio in this embodiment between the worm 8 and the worm wheel 2 is 1:36, whereas for the screw wheel 11 and the auxiliary member 12 this ratio is 1:1. The auxiliary member 12 has a pin 14. A ratchet wheel 15, which in this case has 50 notches 16, can likewise rotate freely about the shaft 13, said notches being uniformly divided over the circumference of the ratchet wheel 15. A simple friction coupling 12a is pro-

3
vided between the auxiliary member 12 and the ratchet wheel 15. The ratchet wheel 15 furthermore has two pins 17 and 18 which are rigidly secured thereto. A pawl 19 can rotate about pin 17, which pawl has a V-shaped extremity 20 and is normally pushed against pin 18 by means of a spring 21 secured to a pin 22a, so that the pin 14 is located in the V-shaped extremity 20 of ratchet 19.

Rigidly connected to the ratchet wheel 15 is a collector 22 of conductive material, in which a sector 23 of non-conductive material is placed. On the outer side of this collector are provided 50 sliding contacts which are rigidly arranged and divided uniformly over 360° , while a sliding contact 25, likewise rigidly arranged, is in contact with the inner side of the collector.

A pawl 26 meshes with the gearing of ratchet wheel 15 and can rotate about a fixed point 27. The position of the pawl is determined by a stationary relay 28, the pawl itself co-operating with an electric contact 29, so that this contact is open when the pawl meshes with the ratchet wheel 15 and is closed when the pawl is attracted by the relay 28.

The driving shaft 10 is driven by an electric motor 31, which may have two directions of rotation, with the interposition of an overload coupling 30. The overload coupling 30 is of known type which switches off when the shaft 10 is loaded above a predetermined value and which automatically switches on again when the overload on the shaft 10 is eliminated. When the connection between the electric motor 31 and the shaft 10 is interrupted, the overload coupling operates in known manner a switch 32. In the case shown, the switch 32 is interrupted when overload occurs and the contact in the switch is restored again when the overload is eliminated. The switch used may be, for example, of the micro-type. Furthermore, a reversing relay 33 is provided which determines the direction of rotation of the electric motor 31.

Two selector means being collectors 34 and 40 determine the positions of the collectors 4 and 22. The selecting collector 34 has a conductive portion 35 having a conductive sector 36, while the portion 37 is insulating. On its periphery there are provided 36 sliding contacts 38 which are fixed and regularly divided over 360° , one fixed sliding contact 39 being provided on its inner side. The selecting collector 40 likewise has a conductive inner ring 41 with a conductive sector 42 and an insulating outer ring 43 and comprises 50 fixed sliding contacts 44, which are arranged, likewise regularly divided over 360° , on the outer side of the collector, one fixed sliding contact 45 being in contact with the inner side of the collector.

Now, the operation of the shaft-positioning mechanism described will be explained hereinafter, it being assumed that a direct-current source is connected to the device, that is to say to the plus terminal at 46 and to the minus terminal at 47. Let it be assumed that a new position of the shaft 1 is desired, so that both the collector 34 and the collector 40 must be rotated; the correct positions of these collectors, corresponding to this new position, may be read for example on a chart. When these positions have been reached, then primarily a circuit extending from 46 through sliding contact 39, sector 36, sliding contact 38, sliding contact 6, collector 4, sliding contact 9, reversing relay 33 to 47 is completed. Consequently, the armature of reversing relay 33 is attracted and the contacts 48, 49 and 50, 51 are closed. At the same time, a circuit extending from 46 through sliding contact 45, collector 40, sector 42, sliding contact 44, sliding contact 24, collector 22, sliding contact 25, relay 28 to the minus terminal 47 has been established. Consequently, the relay 28 is energized and the pawl 26 is attracted, so that it no longer arrests the ratchet wheel 15 and the switch 29 also is closed. The electric motor also has in the meantime been switched into a circuit via 46, contact 50, 51, contacts 48, 49 and the minus-terminal 47 and this

5
motor now starts to rotate in such manner that both the sector-adjusting member 22 and the auxiliary member 12 rotate in the counter-clockwise direction. This is possible, since the shaft 10 and the electric motor 31 are coupled together by the coupling 30. The contact in the switch 32 has also been restored in the meantime.

6
The ratchet wheel 15 and the collector 22 are initially driven by the friction coupling 12a. However, the collector need perform at most only one revolution (expressed exactly: 360° —about 8°) since each new position which corresponds to the position adjusted by collector 40 is then certainly reached. When the collector has reached the new position, the relay 28 is no longer energized (circuit 46—45—41—42—44—24—23—22—25—28—47 is interrupted) and the pawl 26 is released and engages the ratchet wheel 15; furthermore, the switch 29 is opened. However, collector 4 usually has not reached then the new position corresponding to the new position of collector 34 but the auxiliary member, after the pawl 26 has engaged the ratchet wheel, can continue its rotation in the same direction, since on the one hand the reversing relay 33 is still energized and on the other hand the pin 14 can always rotate in the counter-clockwise direction, since the pawl 19 can be lifted. The auxiliary member 12 rotates 36 times as rapidly as the sector-adjusting member 2.

7
When the sector-adjusting member 2 with its collector 4 has also reached the position in which the collector position corresponds to the position of collector 34, the reversing relay becomes de-energized (now circuit 46—39—35—36—38—6—5—9—33—47 is interrupted) and the direction of rotation of the electric motor 31 reverses. This motor in itself now receives current through the switch 32 which is still closed. Now, the auxiliary member 12 also rotates in the clockwise direction till the pin 14 abut against the V-shaped extremity of the pawl 19. The auxiliary member then cannot rotate further and overload on the shaft 10 occurs and the overload coupling 30 becomes operative, with the result that the contact 32 is opened and the electric motor comes to a standstill. During the rotation of the auxiliary member 12 in the clockwise direction, the sector-adjusting member 2 has also rotated in the clockwise direction so that the shaft 1 to be adjusted also rotated in the clockwise direction. However, the collector 4 remains at rest due to the play of pin 3 in the groove 7.

8
In the embodiment shown, the collector 4 has 36 positions; the sector 5 of this collector thus may have at most an angular value which secures that contact is never made with two sliding contacts 6 simultaneously. It will also be evident that the adjusting member 2 likewise has 36 positions of 10° each. When the adjusting member 2 has covered 10° , the auxiliary member 12, as previously mentioned, has covered 360° . However, the ratchet wheel 15 has 50 teeth and this implies that it can occupy any one of 50 positions during one complete revolution. These 50 positions are thus possible within an angular displacement of 10° of the adjusting member 2, so that in total $36 \times 50 = 1800$ preset positions of the shaft 1 are possible.

9
When the shaft 10 passes from a determined position to a new desired position, the initial direction of rotation is always in the same direction and such that the wheel 2 rotates in the counter-clockwise direction. However, collector 4 starts to rotate only when the pin 3 has abutted against the extremity of groove 7. When the correct position of collector 4 has been reached, the movement of the member 2 reverses and pin 3 moves away from the end of groove 7, but the collector 4 remains at rest. Due to the first-mentioned movement, the end of a sector of (in this case) 10° is thus chosen, within which the desired position of the shaft is situated. As soon as this end has been reached and the pin 3 thus has moved the collector into its correct position and hence the shaft to be adjusted into its provisional position, the pin 3

moves away from the end of groove 7 (that is to say the end of the sector) and the shaft 1 is moved into its definite position. From this it follows that the angular value of the groove 7 must not be less than 10° ; however, it is allowed to be larger, since the upper boundary of the groove is immaterial, due to pin 3 never being able to engage this upper boundary. Consequently, the member 2 is actually a sector-adjusting member which primarily determines the end of a sector.

It is by no means necessary for the collectors 34 and 41 to be adjusted simultaneously. When collector 34 is adjusted first, the motor already starts to rotate, but this is not objectionable, since the auxiliary member 12 can keep rotating in the counter-clockwise direction, even when the ratchet wheel 15 is still arrested by the pawl 26. The pin 14, rotating in counter-clockwise direction, then lifts the pawl 19 against the pressure of spring 21 and can continue its rotation. The pawl 26 releases the ratchet wheel 15 only after the collector 40 has also been adjusted and now the ratchet wheel 15 follows the movement of the auxiliary member 12.

In the foregoing it has been assumed that both collectors are rotated, simultaneously or not simultaneously. It is possible, however, that purposely only the collector 34 is adjusted. This case occurs, for example, when the position of shaft 1 must be so varied that a whole number of times 10° must be added to the position or subtracted therefrom. In this case, the position of collector 40 does not vary and the pawl 26 keeps in engagement with the ratchet wheel 15; the sector-adjusting member 2 then rotates in the counter-clockwise direction, till the end of the new section has been reached, the pin 14 continuing its rotation under the pawl 19. When this end has been reached, the movement reverses and as soon as pin 14 has engaged the pawl 19, the new position is reached, which thus differs n times 10° from the previous position.

On the other hand, it is also possible that a new position is desired which differs only by a small angle, for example 3° , from the previous position, the new position being situated within the sector, within which the previous position was located and hence, for example, when passing from 93° to 96° . In this case, only collector 40 is rotated and collector 34 remains at rest. During the rotation of collector 40, the pawl 26 is then immediately lifted and since the relay 33 receives current through contact 29, the motor again rotates in the counter-clockwise direction until collector 22 again has a corresponding position.

In the meantime, the sector-adjusting member 2 has also been driven, but since the desired adjustment of the shaft differs by less than 10° from the previous adjustment, the rotation of the member 2 is now so small that pin 3 cannot engage the end of groove 7 before the reversing relay is already de-energized due to the meshing of pawl 26. The collector 4 thus remains at rest and, after the direction of rotation has reversed, the pin 3 again moves back, but a little farther than the previous position was. As before, the special position of pin 14 with respect to ratchet 19 at the moment of the reversal of the movement determines the extent of the backward movement of pin 3 and hence the ultimate position of shaft 1.

Finally, it is possible that the shaft, instead of being moved from 93° to 96° must be moved from 96° to 93° , in which event, for example collector 40 is rotated a small amount in the clockwise direction. The collector 22 must then be rotated by almost 360° , but in the majority of cases the pin 3 then has already engaged the end of groove 7, so that collector 4 starts to rotate. As soon as this happens, the first circuit is also closed and although the pawl 26 has already meshed after a rotation of collector 22 of almost 360° , the sector-adjusting member 2 and the auxiliary member 12 continue to

rotate until the first 360° have been covered. At this moment, however, the reversing relay is definitely de-energized and now the correct point of adjustment may be found in the reverse direction of rotation in the manner previously described.

It has been mentioned before and has become even clearer from the foregoing that the definite position of the shaft 1 is ultimately determined by the spacial positions occupied by the pin 14 and the pawl 19 when the direction of rotation reverses. In the first place, the two parts always meet with a direction of rotation of the auxiliary member 12 in the clockwise direction, so that any backlash is always eliminated in the same direction, while the directional force, to which the shaft 10 remains subject after the coupling 30 has been interrupted, ensures that such backlash is always eliminated with the same force. Since the unavoidable inaccuracy of the readjustment is transferred with reduction to the ratchet wheel 15, it is also clear that this inaccuracy may be much smaller than in conventional constructions. In practice, an inaccuracy of readjustment of 0.02° may be achieved. It is also clear that the ratio between the speeds per unit-time of the sector-adjusting member 2 and the auxiliary member 12 is solely determined by the number of sectors which the member 2 must be able to choose since after a complete revolution of the auxiliary member 12 the member 2 must have rotated by an angle such that a new sector has been chosen. The transmission ratio between the worm 8 and the sector-adjusting member 2 is thus equal to 36 when the transmission ratio between the screw wheel 11 and the auxiliary member 12 is equal to 1, since there are 36 sliding contacts; the angular value of groove 7 is at least 10° , since each sector is 10° and the angular value of the insulating part 5 on the collector must be smaller than 10° for the same reason.

In view of the small time of adjustment which in certain cases is desired and the speed at which the auxiliary member 12 and the ratchet wheel 15 rotate, it may be desirable in view of the release time of relay 28, that the ratchet wheel 15 rotates more slowly than the auxiliary member 12. This is possible if it is taken into consideration that the spacial positions of the pawl 19 and the pin 14 with respect to one another determine the position of the shaft, as previously mentioned. It is thus fundamentally possible, and in certain cases desirable in practice that the ratchet wheel 15 is driven by a retarding gear, and if necessary by a separate electric motor. It is in certain cases even simpler to arrange the ratchet wheel 15 on the shaft 1 freely rotatable, and to provide a light friction coupling between the sector adjusting member 2 and the ratchet wheel 15, it then naturally being necessary that the pin 14 can continue to co-operate with the pawl 19.

Finally, it has been assumed in the foregoing that the shaft 1 is the shaft to be positioned and that this shaft can be positioned in 1800 positions only through an angle of 360° . However, in certain cases it is desirable that the shaft to be adjusted should be capable of rotating a plurality of times 360° . Such is the case, for example, with a shaft carrying a sliding contact which constitutes tappings of an inductance coil. Such a shaft may then be rigidly connected to the driving shaft 10, so that adjustments through at most $36 \times 360^\circ$ are possible.

It is finally also possible for the 50 positions determined by the teeth of the ratchet wheel 15 to be distributed irregularly over 360° . In this case, the difference between the possible positions, instead of being n times 0.2° , is equal to another amount which is not a multiple of 0.2° . It must then be considered, however, that this irregularity is repeated in every 10° , that is to say in each sector of the shaft to be adjusted. This is not objectionable for certain purposes. Furthermore, one is not limited by sectors of 10° , but other values may be chosen

as well. It is even possible to utilize sectors of relatively different values. In this case, the transmission mechanisms between the driving shaft and the adjusting member may be variable for each revolution, for example by means of elliptical gear wheel or similar members.

The shaft-positioning mechanism as described is suitable not only for wireless telecommunication devices, but also for use as a dividing device for machine tools and similar machines, where accurate and rapid adjustment of the work-piece to be processed or of the tools is desired.

What is claimed is:

1. A shaft positioning mechanism for positioning a shaft in a plurality of preset positions comprising first and second rotary adjusting members, said first adjusting member being rigidly connected to said shaft to be positioned, a first collector rotatably mounted on said shaft to be positioned, a lost motion connection between said first adjusting member and said first collector, a second collector operatively connected to said second adjusting member, selector means operatively connected to said rotary adjusting members, a motor, a main drive shaft operatively connected to said motor provided with transmission means for said rotary adjusting members, the transmission means between said main drive shaft and said first rotary adjusting member having a greater speed reduction than the transmission means between said main drive shaft and the second rotary adjusting member, said first rotary adjusting member during positioning of said shaft determines the end of the lost motion sector within which the selected position is situated, and means including said motor for rotating both said first and second rotary adjusting members in the opposite direction to the original direction of rotation to position said shaft in the selected position within the sector selected by said first rotary adjusting member starting from the end of the sector selected by said first rotary adjusting member.

2. A shaft positioning mechanism as claimed in claim 1 wherein all the sectors traversed by said rotary adjusting members have the same angular value and whole parts of 360°.

3. A shaft positioning mechanism as claimed in claim 1 wherein said selector means includes a collector and a coupling between said second rotary adjusting member and said collector permitting the free movement of said second rotary adjusting member relative to said collector.

4. A shaft positioning mechanism as claimed in claim 3 wherein the free movement of said second rotary adjusting member relative to said collector is possible through an angle having at least the same value as the angular value of said sector.

5. A shaft positioning mechanism for positioning a shaft in a plurality of preset positions comprising first and second rotary adjusting members, said first adjusting member being rigidly connected to said shaft to be positioned, a first collector rotatably mounted on said shaft to be positioned, a lost motion connection between said first adjusting member and said first collector, a second collector operatively connected to said second adjusting member, selector means operatively connected to said rotary adjusting members, a motor, a main drive shaft operatively connected to said motor with transmission means for said rotary adjusting members, the transmission means between said main drive shaft and said first rotary adjusting member having a greater speed reduction than the transmission means between said main drive shaft and the second rotary adjusting member, said first

rotary adjusting member during positioning of said shaft determines the end of the lost motion sector within which the selected position is situated, and means including said motor for rotating both said first and second rotary adjusting members in the opposite direction to the original direction of rotation to position said shaft in the selected position within the sector selected by said first rotary adjusting member starting from the end of the sector selected by said first rotary adjusting member, said second rotary adjusting member being constituted of two parts, one part being a ratchet wheel and having a collector rigidly connected thereto and the other part being an auxiliary member driven by said driving shaft, a coupling provided between said two parts permitting free rotation of said auxiliary member with respect to said ratchet wheel in one direction of rotation whereas in the other direction of rotation the auxiliary member may perform a rotation of at most 360° with respect to said ratchet wheel.

6. A shaft positioning mechanism as claimed in claim 5 further comprising a pawl, means electrically operating said pawl relative to said ratchet wheel, the position of said ratchet wheel being determined by said collector rigidly connected thereto.

7. A shaft positioning mechanism as claimed in claim 5 wherein said ratchet wheel and collector are adapted to rotate about said drive shaft, and a friction coupling is provided between said two parts.

8. A shaft positioning mechanism as claimed in claim 5 further comprising a second drive shaft operatively connected to said main drive shaft driving said ratchet wheel with its collector.

9. A shaft positioning mechanism for positioning a shaft in a plurality of preset positions comprising first and second rotary adjusting members, said first adjusting member being rigidly connected to said shaft to be positioned, a first collector rotatably mounted on said shaft to be positioned, a lost motion connection between said first adjusting member and said first collector, a second collector operatively connected to said second adjusting member, selector means operatively connected to said rotary adjusting members, a motor, a main drive shaft operatively connected to said motor with transmission means for said rotary adjusting members, the transmission means between said main drive shaft and said first rotary adjusting member having a greater speed reduction than the transmission means between said main drive shaft and the second rotary adjusting member, said first rotary adjusting member during positioning of said shaft determines the end of a sector of the total angle of rotation within which the selected position is situated, and means including said motor for rotating both said first and second rotary adjusting members in the opposite direction to the original direction of rotation to position said shaft in the selected position within the sector selected by said first rotary adjusting member starting from the end of the sector selected by said first rotary adjusting member, and said second rotary adjusting member being operatively connected to said main drive shaft and driving said shaft to be positioned.

10. A shaft positioning mechanism as claimed in claim 1 wherein said shaft to be positioned is directly coupled with said main drive shaft.
